Application November 12, 1936, Serial No. 110,415

3 Claims. (Cl. 201—63)

This invention relates to new and novel resistors of small internal and stray capacitance which are particularly adapted to high frequency circuits.

5 An object of this invention is to simplify and improve small capacity resistors generally.

Another object of this invention is to increase the loading capability in general of resistors of low internal and stray capacitance, in other 10 words, to provide a resistor of low internal and stray capacitance with improved means of heat dispensation.

It can also be stated that by this invention, there is provided resistor units of small physical 15 dimensions having low values of distributed capacitance and capacitance leakage to the surrounding supporting elements.

Thus, one of the objects of this invention is to provide a small resistor with increased cooling 20 means so that it will be able to carry a higher current load. The gain from this procedure is then that the resistor can be made very small and thus have low internal as well as stray capacitance, which is an important feature in 25 short wave or high frequency circuits, such as in resistance coupled amplifiers handling wide frequency bands. An increased capacitance effect will cause an increasing reactive (capacitively reactive) current to be introduced at the higher 30 frequencies together with the current determined by the resistive values which will result in undesired distortion.

A feature of this invention is the placing of a resistive material in an efficient electrical insulating and cooling medium to reduce the 35 physical dimensions of the resistor.

Another feature of this invention is the method 40 of making improved enclosed resistor units and also the means of supporting and connecting them in a circulating fluid cooling system. The improved resistor of this invention may be used in the circuit of a high power, resistance coupled linear amplifier for very high frequencies in the order of 20,000,000 to 2,000,000 cycles. The inherent capacitance of the ordinary resistor becomes a serious factor that must be reckoned with when used in high frequency circuits.

The outstanding factors contributing to the 45 undesired capacitance effects of resistors known in the prior art are the large physical dimension of the ordinary resistors made necessary because of the need for heat dissipation, the spacing of the wires, the dielectric constant of the binder for the wires, and the method of the distribution of the binder, also the dielectric constant

of the mechanical support for the wires or resistance material.

There have been several methods suggested in the past to reduce the above mentioned factors to a fair minimum as, for example, by the use of materials having high heat resistivity and also by supporting the wires or resistive element by a minimum amount of insulating material and allowing air currents to freely circulate around the resistance wire; however, such 10 methods are still unsatisfactory for the higher frequencies.

Briefly, by my invention I propose to greatly 15 improve the low capacitance resistors known in the prior art by mounting the resistance element within a tube of very high grade insulating material which at the high frequencies has a minimum dielectric effect upon the capacitance. The 20 resistance element may be either that of a coated film, a wire, or a filament; the resistivity of the material may be of a high or low value. The tube of insulating material has a physical length greater than the length of the resistance element. The resistance element is placed within a circulating fluid system. By the term "minimum dielectric effect" I mean the use of a good 25 dielectric material, that is, a material having a low dielectric loss, to mechanically support the resistive element so that the dielectric constant of the resistor portion of a high frequency circuit will be small and the losses low when the 30 resistor is placed in high frequency circuits.

Although a resistive element which is a conductor has only pure resistance when placed in a direct current circuit, when placed in a high 35 frequency circuit, the resistor portion of the high frequency circuit has in addition to the resistance, a series inductance which is caused by the length of the conductor and also its shape. Likewise, in shunt with the resistance and the series inductance, there is a shunt 40 capacitance, this capacitance being caused by the insertion of some form of mechanical support which in this invention is the glass tube 2, and therefore as it is desirable to keep the dielectric losses to a minimum, it becomes necessary to employ as little insulating material in the circuit as possible. Likewise, it is desirable 45 to keep the dielectric constant of the material low so that the total dielectric effect is maintained at a minimum amount.

This invention will best be understood by referring to the accompanying drawings, in which:

Fig. 1 is a schematic diagram of a fluid circulating coil system;

Fig. 2 is a detailed view of the improved resistor element located within a tube of material having a minimum low dielectric constant at the high frequencies;

5 Fig. 3 is a plan view of Fig. 2;

Fig. 4 is a modification of Figs. 2 and 3 wherein the resistance element is a straight resistance wire;

10 Fig. 5 is a modification of Figs. 2, 3 and 4 wherein the resistance element is in the form of a helical coil of resistance wires; while

Fig. 6 is a schematic diagram showing a modification of Fig. 1;

15 Fig. 7 is a schematic diagram of a water cooling system; and

Fig. 8 is a schematic diagram of an air cooling system.

Referring now in detail to Fig. 1, a schematic diagram is shown of a symmetrical arrangement 20 of two resistors located within a circulating fluid and electrical insulating system such as oil, or the like. The resistance element 1 is shown located within the tubes 2 which are of high grade insulating material having a minimum dielectric 25 effect, such as "Pyrex," glass, isolantite, etc. The insulating tubes 2 are secured to a mounting panel 3 by means of flanges 4 and are coupled to circulating metallic pipes 5 and 6 by means of coupling fittings 7 and 8. The upper pipe 5 30 is connected to the top of a fluid radiator 9 of copper, which is provided with cooling fins 10. This radiator can be additionally cooled by an external water circulating or refrigeration system, air blast, etc. The lower circulating pipe 6 35 is coupled to the radiator at a point 11. The other half of the symmetrically arranged cooling system is arranged similarly to that mentioned above, except that there is provided a tube 12 which is of necessity longer than section 40 5 due to the fact that it is located at a greater distance from the radiator 9. Likewise, at the lower portion of the radiator, a circulating tube 14 is connected to the lower portion of the resistance tube 2.

45 In Figs. 2 and 3, there is shown in detail the preferred embodiment of this invention wherein resistance element 1 is in the form of a metallized coating on the central portion of the inner wall of insulating tube 2. The ends of the coating 50 1A terminate in a metal-like band 20 which is connected to a hollow terminal stud 21 through which a wire 22 connects band 20 with terminals 21. To protect the supporting and sealing tip 23, there is provided a metallic bell-like member 55 24. The terminal 21 is provided with suitable nuts 25 and washers 26. To provide fluid type connections to the insulating tube 2, there is provided in each end of the tube a series of grooves 19 to which any suitable coupling fitting is 60 fastened such as rubber hose with metallic bands surrounding the grooved portion 19. A coated resistor is particularly valuable in circuits where also a low inductive reactance is desirable. The coating of the resistor may, of course, be on 65 either or both sides of a strip or on the inside, outside or both of a cylinder. The cylinder may also be the resistance material, itself. The main feature is that they should be immersed in an efficient cooling insulating medium so that the 70 physical dimensions of the resistor may be reduced. Further information relative to the resistance film formed on an insulating surface may be had by referring to the Hansell docket 11083, filed Feb. 6, 1936, Serial No. 62,587.

75 The modification shown in Fig. 4 is of similar

construction to that of Figs. 2 and 3, except that instead of the coated film within the inner wall of the tube 2, the resistive element is in the form of a non-inductive metallic rod-like resistance 5 27. This rod may be of any suitable resistance material such as Monel metal, nickel silver, Nichrome, Advance, or the like. The resistance rod 27 is located substantially in the central portion of tube 2 and may be of any suitable configuration such as a ribbon square or round 10 rod of that of a wave band with a wave-like configuration to provide increased cooling surface yet sufficiently limited in curvature to prevent the formation of undesired electrical inductance.

The tube 2 is provided with terminal members 15 similar to that mentioned above with reference to Figs. 2 and 3 and the ends of the tube are provided with grooves 19 to provide fluid type connections with suitable coupling means.

Referring now to Fig. 5, a resistance wire 30 20 in the form of a helical coil is located substantially in the center of the insulating tube 2. Each end of the coil is provided with a hollow terminal stud 15 through which wire 1 is soldered at a point 16, electrical connections being taken from 25 stud 15 and secured by means of nuts 17 and washers 18. Fluid-tight connections are made to the insulating tube as described above, with reference to Figs. 2 and 3, by providing in each end of the tube a series of grooves 19 to which 30 any suitable coupling fitting is fastened. This helical form naturally has a large amount of electrical inductance; therefore, its use is more limited when placed in a high frequency circuit than the form shown by Figures 2, 3 and 4. 35

The schematic diagram shown by Fig. 6 is generally similar to that of Fig. 1, except that the lower pipes 6 and 14 of the circulating fluid system are provided with a pump to force the fluid in circulation, whereas the system shown in 40 Fig. 1 is that generally known as the thermosyphon system. The circulating fluid for either system can be either hydrogen, oil or any other fluid having the requisite insulating qualities.

The radiator 9 may also be more or less integral 45 with the panel of the set. The radiator may also be cooled by an external water circulating system, as shown by Fig. 7, wherein a tank 20 contains a circulating fluid, such as water 21 or the like which may be circulated by a pump 22. Radiator 50 9 is supported in the bottom of the tank by supports 23; to provide a fluid-tight container bushings 29 are provided.

Fig. 8 shows a fan or blower 26 for blowing a blast of cool air upon radiator 9 and while only 55 one fan or blower is shown, a greater number may be provided and arranged to cool any part of radiator 9, or fan 26 may be placed outside of tank 20 of Fig. 7 to provide additional cooling of the circulating fluid 21. 60

This invention is not to be limited to the modifications shown as it is evident to those skilled in the art that the invention may take other forms within the spirit and scope of the same, and therefore should not be limited except 65 by such limitations as are imposed in the appended claims.

What is claimed is:

1. In a non-inductive resistance element for use in a high frequency circuit, an insulating tube 70 open at each end and having substantially low dielectric effects upon said resistance when placed in said high frequency circuit, a metallic resistive element within said insulating tube, liquid cooling means for passing a liquid through said insulating 75

5 tube to cool said resistive element, terminal means including a projecting portion provided within the side walls of said tube for connecting the resistance with a hollow stud for providing external connections to said high frequency circuit, and mechanical coupling means located at the ends of the tube for coupling said resistance with said liquid cooling means.

10 2. In a non-inductive resistance element for use in a high frequency circuit, an insulating tube open at each end and having substantially low dielectric effects upon said resistance when placed in said high frequency circuit, a metallic resistive element within said insulating tube, liquid cooling means for passing oil through said insulating tube to cool said resistive element, terminal means including a projecting portion provided within the side walls of said tube for connecting the resistance with a hollow stud for providing external connections to said high

frequency circuit, and mechanical coupling means located at the ends of the tube for coupling said resistance with said liquid cooling means.

3. In a non-inductive resistance element for use in a high frequency circuit, an insulating tube 5 open at each end and having substantially low dielectric effects upon said resistance when placed in said high frequency circuit, a metallic resistive element within said insulating tube, liquid cooling means for passing a liquid through said insulating tube to cool said resistive element, terminal means including a projecting portion provided within the side walls of said tube, a metal band connected to said terminal means for connecting the resistance with a hollow stud for providing external 10 connections to said high frequency circuit, and mechanical coupling means located at the ends of the tube for coupling said resistance with said liquid cooling means.
